LOOM GAUGE

Thomas J. Oliver, Birmingham, Ala.

Application December 5, 1942, Serial No. 468,004

5 Claims. (Cl. 33—181)

This invention relates to a gauge for use in fixing looms, whereby the lay may be readily set to run square with the loom and the reeds set in line with the backs of the shuttle boxes and other setting up operations performed, and has for an object the provision of a device of the character designated which shall be simple of design and operation and which shall be adapted for use in a variety of operations of setting and adjusting the operating parts of a loom.

In the fixing, or setting up of looms, the squaring of the lay with the loom, the proper timing of the eccentric cranks and the throw of the eccentrics are extremely important. The position of the shuttle boxes in regard to the race plate and the position of the reeds with respect to the loom all contribute to the proper working of the loom. If any of these parts are out of line, or are not running true, the shuttle may be thrown out of the shed, causing a stopping of the loom and endangering the workmen, as well as breaking or damaging shuttles. The principal object of this invention, therefore, is to provide a gauge by which the working of the lay with its shuttle boxes, race plate, and reeds may be properly aligned and properly timed.

A device embodying features of my invention is illustrated in the accompanying drawings, forming a part of this application, in which

Fig. 1 is a plan view of my improved gauge together with the parts of the loom with which it is associated;

Fig. 2 is an end view of the same;

Fig. 3 is a sectional view taken along the line III—III of Fig. 1; and

Fig. 4 is a sectional view taken along the line IV—IV of Fig. 1.

Referring to the drawings, my improved gauge comprises a rear cross beam 10 which is secured by means of bolts 11 to arch support 12 of a loom. In mounting the gauge, the arch is removed and the cross beam 10 bolted down to the arch support through slotted holes 15 which permit lateral adjustment of the beam. The cross beam 10, as may be seen in Fig. 2, is preferably in the form of an angle bar and for the purpose of positioning it on the arch support 12 there are secured lugs 13 to the rear of the beam which take a bearing on the arch support.

The cross beam 10 is centered with respect to the loom by means of rods 14 and 16 mounted in suitable bearings 17, on the underside of the cross beam 10. Springs 18 and 19 surround the rods and bear against collars 21 and 22 respectively, on the rods 18 and 19, to urge them out-

wardly against the inner sides of the arch support 12. Pointers 23 and 24, carried by the rods 14 and 16, extend up over the lower flange of the cross beam 10 to cooperate with a scale 26 to indicate the position of the cross beam with respect to the loom. The cross beam being bolted down through the slotted holes 15 can be shifted until the indicators 23 and 24 show that the beam is centrally located with respect to the loom.

At the ends of the cross beam 10 are vertical supports 27 and 28 which are made higher than the top reed rod 29. Secured to the upper ends of the supports 27 and 28 are side beams 31 and 32 which extend forwardly over the lay and reed rods and are secured at 33 and 34 respectively to the breast beam 36 of the loom. The side beams, as may be seen in Fig. 1, extend a considerable distance beyond the breast beam 36. Joining the forward ends of the side beams 31 and 32 is a front cross beam 37. The rear cross beam 10 and front cross beam 37 should both be rigidly joined to the side beams 31 and 32 and should be checked before each use to be sure they are in proper relation to each other; that is, the side beams 31 and 32 should extend normal to the cross beams in order to obtain accurate results.

Pivotedly mounted on the front cross beam 37 at 38, 39, and 41 are forwardly extending arms 42, 43, and 44 respectively. Each of the forwardly extending arms is made up of channel members 45 and 46, as may be seen in Fig. 3, and house between the channels movable gauge elements 47 which are biased rearwardly by means of springs 48. A pointer 49, carried by each of the gauge elements 47, cooperates with a scale 51 on the channel 45 to indicate the relative positions of the gauge elements with respect to the housing.

Pivotedly mounted on the rear end of each of the gauge elements 47 is a bifurcated feeler head 52. Each of the feeler heads 52 is provided with slots 53 to receive a straight edge 54 in position to engage the reeds 56 as the lay moves forwardly. As shown, the feeler heads are pivoted to swing in a horizontal plane and have pointers 57 rigidly secured thereto and extending forwardly over the arms 42, 43, and 44. A scale 58 carried by each of the gauge elements 47 visually indicates the angular displacement of the feeler heads by reason of the engagement with the reeds. After the reeds are checked at the plurality of points provided by the three feeler heads 52, it is contemplated that a single straight

edge will be mounted in all of the slots of the feeler head to extend entirely across the loom and thus check the alignment of all the reeds.

From the foregoing description the manner of use of my improved loom gauge will be apparent. Whenever it is desired to fix, or set up, a loom, the arch is removed and my improved gauge is applied by bolting it down to the arch support 12 through the slotted holes 15, as shown in Fig. 2, the lugs 13 insuring that the cross beam will be set square with the loom. The cross beam is shifted until the pointers 23 and 24 show that it is centrally located with respect to the arch support 12 whereupon the bolts 11 are tightened down to hold it firmly in place. The side beams 31 and 32 are then secured to the breast beam 36 by means of the bolts 33 and 34; the straight edges 54 are mounted in the slots 53, and the loom is turned over to cause the crank shaft 59 to rotate and move the lay 61 forwardly. As the lay moves forwardly, the pointers 49 coacting with the scales 51, visually indicate the amount of forward movement of the lay. If it should move forward unequally across the loom due to a sprung crank shaft, damaged connecting rods, a warped lay, or whatever cause, the indicators will show the defect, and the workmen may thereupon set about to apply the proper correction. At the same time, the alignment of the reeds may be indicated both with respect to each other and to the backs of the shuttle boxes (not shown). By the use of my improved gauge, it will be seen that the parts of a loom may be fixed to move properly and squarely with the loom, and thus secure its proper, safe operation.

While I have shown my invention in but one form, it will be obvious to those skilled in the art that it is not so limited, but is susceptible of various changes and modifications, without departing from the spirit thereof, and I desire, therefore, that only such limitations shall be placed thereupon as are specifically set forth in the appended claims.

What I claim is:

1. A gauge for trueing up the lay and reeds of a loom comprising a rectangular frame, means to attach the frame to the loom, means to center the frame with respect to the loom, feeler means yieldingly mounted on the frame and adapted to engage the reeds as the lay moves forward, and indicator means associated with the feeler means to show the amount of movement of the feeler with respect to the lay as the lay moves forward.

2. A gauge for trueing up the lay and reeds of a loom comprising a rectangular frame, means to attach the frame to the loom, means to center the frame with respect to the loom, feeler means yieldingly mounted on the frame and adapted to engage the reeds as the lay moves forward, indicator means associated with each of the feeler

means to show the amount of movement of each feeler with respect to the lay as the lay moves forward, feeler heads included in the feeler means and mounted to swing in a horizontal plane, and means to indicate the angular displacement imparted to each of the feeler heads by the reeds.

3. In a gauge for trueing up the lay and reeds of a loom, a frame adapted for attachment to the loom, means to true up the frame with respect to the loom, a plurality of arms pivotally mounted on the frame and extending rearwardly toward the lay, spring pressed elements associated with the arms and adapted to yield responsive to forward movements of the lay, means to show visually the amount of yielding movement of each of said elements relative to the arm with which it is associated, feeler heads pivotally mounted on the rearward ends of each of said yielding elements and adapted to engage the reeds, and means to indicate the angular displacement of each of the feeler heads imparted by the reeds.

4. In a gauge for trueing up the lay and reeds of a loom, a frame adapted for attachment to the loom, means to true up the frame with respect to the loom, a plurality of arms pivotally mounted on the frame and extending rearwardly toward the lay, spring pressed elements associated with the arms and adapted to yield responsive to forward movements of the lay, means to show visually the amount of yielding movement of each of said elements relative to the arm with which it is associated, feeler heads pivotally mounted on the rearward ends of each of said yielding elements and adapted to engage the reeds, means for attaching a straight edge to each of the feeler heads to engage the reeds, and means to indicate the angular displacement of each of the heads imparted by the reeds.

5. In a gauge for trueing up the lay and reeds of a loom, a frame comprising a rear cross beam adapted to be secured to the loom, forwardly extending side beams and a front beam, means to secure the rear cross beam and side beams to the loom, means to center and adjust the position of the frame on the loom, a plurality of rearwardly extending arms pivotally mounted on the front beam, a feeler head pivotally mounted on each of the arms in position to be engaged by the reeds upon forward movements thereof, means providing relative yielding movement between the feeler heads and the rearwardly extending arms responsive to forward movements of the lay, means to indicate the amount of relative movement between the feeler heads and the arms, and other means to indicate the relative angular movement of the feeler heads with respect to the rearwardly extending arms.
